Primary Examiner — Kevin Rudzinski(74) *Attorney, Agent, or Firm* — Banner & Witcoff, Ltd.(57) **CLAIM**

The ornamental design for a display screen with graphical user interface, as shown and described.

DESCRIPTION

The FIGURE is a front view of a display screen with graphical user interface showing our new design.

The broken lines shown in the FIGURE illustrate the display screen and portions of the graphical user interface and form no part of the claimed design.

1 Claim, 1 Drawing Sheet(56)
